UNITED STATES PATENT OFFICE.

MARY WHEELER AND EDITH MAY BATES, OF LOS ANGELES, CALIFORNIA.

SNAP-FASTENER.

1,357,918.

Specification of Letters Patent.

Patented Nov. 2, 1920.

Application filed April 26, 1920. Serial No. 376,829.

To all whom it may concern:

Be it known that we, MARY WHEELER and EDITH MAY BATES, citizens of the United States, residing at Los Angeles, in the county of Los Angeles and State of California, have invented new and useful Improvements in Snap-Fasteners, of which the following is a specification.

This invention relates to improvements in snap fasteners and the principal object of 10 the invention is to provide means whereby the two members of the fastener may be detachably connected with the garment so that they may be removed therefrom whenever 15 desired.

Another object of the invention is to form both the socket and the stud in metal plates and to provide each plate with a safety pin device for detachably securing it to the 20 garment.

In describing our invention in detail, reference will be had to the accompanying drawings wherein like characters denote like or corresponding parts throughout the 25 several views, and in which:—

Figure 1 is a perspective view of the male element or member.

Fig. 2 is a like view of a female member.

Fig. 3 is a sectional view through the two 30 members when in assembled position.

Fig. 4 is a rear view of one of the members.

Fig. 5 is a view of the blank from which one of the members is formed.

In the drawings we have shown the parts 35 drawn to an enlarged scale so that the details of construction can be seen and understood.

Each element comprises a plate 1 which 40 has ears 2 formed on its sides adjacent one end, the ears being rolled over to form pin receiving eyes. The opposite end of the plate is rolled over, as at 3, to form a bearing for the cross piece of the substantially 45 U-shaped pin 4 so that this pin is hingedly secured to the plate. Its ends are adapted to engage the eyes formed by the ears 2, the device being somewhat similar to the well known safety pin. The pin being 50 formed of spring metal so that the limbs may be pressed inwardly between the eyes and then they will spring outwardly through the space between the edges of the ears and the plate and thus engage the eyes.

Each plate is provided with a central depression 5, the depression in the plate of the male member A being formed in the face of the plate which carries the pin so as to form the stud 6 on the opposite face of said plate while the depression on the plate of the female member B is formed in the opposite face so that the stud 6 may enter said depression and thus the two plates will be held together.

As will be clearly understood the plates 65 are detachably secured to the garment by the pins so that the stud on one plate will be outermost and the depression in the other plate will be outermost and when the two plates are pressed together the stud will 70 snap into the depression and thus hold the two plates of the garment together. The two parts of the fastener may easily and quickly be detached from the garment whenever desired or necessary so that the garment 75 may be washed or cleaned without the fasteners interfering with the operation.

It is thought from the foregoing description that the advantages and novel features of our invention will be readily apparent. 80

We desire it to be understood that we may make changes in the construction and in the combination and arrangement of the several parts, provided that such changes fall within the scope of the appended claim. 85

What we claim is:—

A fastening device of the class described comprising a pair of plates of T-shape with the arms of the T rolled inwardly longitudinally of the plate to form open loops on one 90 face of the plate and one end of each plate being rolled transversely upon the same side of the plate to form a bearing, a U-shaped pin having its cross piece engaging said bearing and its ends adapted to engage the open loops, one plate having a depression thereon to form a socket on that side of the plate opposite from the loops and the other plate having a depression therein to form a projection on the side opposite from the loops, said projection being adapted to engage the depression on the other plate to 95 from a snap fastener. 100

In testimony whereof we affix our signatures.

MARY WHEELER.
EDITH MAY BATES.
